UNITED STATES PATENT OFFICE.

GEORGE W. CLENDON, OF PIERMONT, NEW YORK, ASSIGNOR TO COMBUSTION ENGINEERING CORPORATION, A CORPORATION OF NEW YORK.

PULVERIZED-FUEL BURNER.

Application filed June 12, 1925. Serial No. 36,573.

This invention relates to means for burning pulverized fuel and it is especially useful in the burning of such fuel under stationary boilers.

5 One of the primary objects of the burner is to give a complete and rapid mixture of fuel and air, thereby affording complete combustion with a short, hot flame, the advantage of which is, among other things, 10 that a small setting may be employed.

Another object of the invention is to provide a burner construction in which coking of the fuel at the burner is minimized, if not completely eliminated.

15 Another object of the invention is to provide a burner which may be regulated to give any desired flame within reasonable limitations.

More specifically considered, the invention 20 consists in the combination and arrangement of parts herein set forth.

How the foregoing, together with such other objects as may hereinafter appear, or are incident to my invention, are realized, 25 is illustrated in the accompanying drawing, which is a sectional view of one form of burner embodying my improvements.

Referring now to the drawing, the reference character A denotes the combustion chamber, having one or more openings 7, 30 thru the wall thereof. Over this opening is secured the burner indicated as a whole by the reference letter B. This burner comprises a casting 8, preferably circular in cross section, terminating in the bell 9, which constitutes the discharge end thereof. The inner end of the member 8 is flanged for coupling to the powdered fuel supply line 10 and is also provided with a regulating 35 means such as the damper 11. Within the tubular member 8 is a second cone or bell 12, the two members cooperating to provide an annular channel 13. The inner bell terminates short of the outer bell and the space 40 between the bells at the discharge end of the inner bell is more restricted than elsewhere. Air under control of the damper 14 is supplied to the inner bell from the air conduit 15 and the extension 15^a thereof, which latter constitutes a part of the burner. The inner or discharge end of the extension 15^a is formed into a somewhat circular chamber 15^b which surrounds the bell 9, the wall 15^c thereof being arranged so as to deflect the 45 air supply thru the extension 15^a in the

manner indicated by the arrows. The air supplied to the annular chamber 15^b is under the control of the damper 16.

The operation is as follows:

Preferably from 10 to 15% of the air for 60 combustion is utilized to carry the fuel thru the pipe 10 to the burner, the fuel discharging between the two bells in a hollow frusto-conical stream. Into this stream additional air is introduced thru the bell 12, and still 65 additional air is supplied to the exterior of the stream of fuel thru the chamber 15^b, this latter air being directed angularly with respect to the cone. The air entering thru the inner bell helps to cool the burner and helps 70 to hold the flame away from the burner, in cooperation with the air admitted thru the chamber 15^b. Thus, detrimental coking at the burner is prevented. The air from the chamber 15^b mixes with the fuel and also 75 promotes admixture of the air within the cone with the fuel in the cone, the violence of the mixture being dependent upon the pressure of the air and relative supplies. By proper manipulation of the burners a 80 violent mixture may be set up to produce a quick, short, hot flame or the flame may be lengthened out or softened. One or two burners may suffice for a chamber.

What I claim is:

1. A pulverized fuel burner comprising in combination, inner and outer coaxially mounted bells forming an annular fuel inlet passage therebetween, said bells being configured and proportioned to discharge the 85 fuel from said passage in a frusto-conical sheet diverging from the burner, means for admitting air thru said inner bell and means for admitting air from around the outer bell into the fuel stream in a frusto-conical sheet 95 converging toward said stream.

2. A pulverized fuel burner comprising in combination, inner and outer coaxially mounted bells forming an annular fuel inlet passage therebetween, said bells being 100 configured and proportioned to discharge the fuel from said passage in a frusto-conical sheet diverging from the burner, means for admitting air thru said inner bell and a casing surrounding the bells adapted to discharge a frusto-conical sheet of air converging 105 toward the fuel stream.

In testimony whereof, I have hereunto signed my name.

GEORGE W. CLENDON.
